PORTABLE POWER OPERATED WASHER FOR JEWELRY, DENTURES AND THE LIKE

Opal G. Hamm, P.O. Box 104, Skippack Pike, Center Square, Pa.

Filed Dec. 23, 1964, Ser. No. 83,136

Term of patent 14 years

(Cl. D49—1)

FIG. 1 is a perspective view of the portable power operated washer for jewelry, dentures and the like embodying my new design;

FIG. 2 is a side elevational view to reduced scale of the washer of FIG. 1, the appearance of the far side being substantially a mirror image of the near side shown in elevation therein; and

FIG. 3 is a top plan view thereof taken on a reduced scale.

The rear side, which is not shown, is substantially flat and plain, except as is indicated.

I claim:

The ornamental design for a portable power operated washer for jewelry, dentures and the like, as shown and described.
